Att'y's.

UNITED STATES PATENT OFFICE.

SIDNEY W. KNIGHT, OF LONDON, ENGLAND, ASSIGNOR TO PARKER BROTHERS, OF SALEM, MASSACHUSETTS, A CORPORATION OF MAINE.

GAME APPARATUS.

Application filed October 21, 1924. Serial No. 744,933.

To all whom it may concern:

Be it known that I, SIDNEY W. KNIGHT, a subject of the King of England, and resident of London, England, have invented 5 new and useful Improvements in Game Apparatus, of which the following is a specification.

This invention relates to an amusement device or game which simultaneously presents a test of the player's skill as well as a 10 determination of the element of chance.

The device consists essentially of one or 15 more pockets or buckets held in spaced relationship, preferably with their openings upward or slightly inclined, and an independently adjustable catapult with which suitable projectiles may be thrown toward and into the several pockets from varying 20 distances and positions.

20 A preferred embodiment of the invention will be described in the form shown by the accompanying drawings, in which:—

Fig. 1 is a diagrammatic side view of the game, assembled for playing;

25 Fig. 2 is a front view of the game board;

Fig. 3 is an enlarged perspective view of the catapult; and

Fig. 4 is an enlarged view and cross-section of the projectile, which is shown in 30 the form of a bottle.

Referring to the drawings, 1 represents a plain board, having vertical slots 2 at the bottom edge, adapted to fit into similar slots in the pair of supports 3, which 35 thus serve to retain the board in upright position upon the table top or other flat surface 4. In spaced relation upon the face of the board there are mounted a plurality of pockets, those in the described instance taking the form of buckets 5 having cavities 6 of appropriate size and shape and provided with holes 7 near the upper rim, by which they are hung upon the hooks 8 40 screwed into the board 1. One of the numerals 9 (for example, 10, 25, 50, 75 or 100, as shown) is placed adjacent each of the buckets, to indicate the score to which 45 the player is entitled.

The catapult or spring trap 11 comprises a flat base 12, and a flexed spring member 13, fastened to the base at one end and to

a small carrier block 14 at the other. In the top face of block 14 there is provided a socket 15 to receive the projectile, and a projection 10 (Fig. 1) by which it may be flexed downwardly, with the finger.

The projectile 16 may conveniently be made of wood and in the shape of a bottle. A recess 17 is provided in the bottom, into which there is inserted a counterweight such as the lead plug 18, to stabilize the projectile, and to permit its being of such size and shape as to rest upon the carrier 14 and to be received by any one of the 55 buckets 5.

From the foregoing description, the mode of playing the game will be obvious. After setting up the board 1, in an upright or vertical position upon the supports 3 preferably on a flat surface 4 and adjusting the buckets to hang vertically thereon, the catapult 11 is placed at a suitable distance and directed toward one or another of the buckets. A bottle is then placed in the socket 15 of the block (as shown in Fig. 1) 60 and the carrier depressed by the finger with a pressure calculated to throw or toss the bottle the necessary distance and into one of the buckets. The carrier is then suddenly released whereupon the bottle describes a trajectory as shown by dotted line 19 and either falls into a bucket or to the table 4. The bucket into which it drops determines the score by the numeral 9 adjacent to it, thus 100 for the central bucket, etc. Other rules and methods of scoring 65 may of course be substituted at will. Other forms of the pockets and projectile may be designed and the catapult also may be modified, but such alterations are incidental to the main features of the invention and are comprehended in the above 70 description and by the following claims.

I claim:

1. A game board comprising a flat board, 75 a hook thereon, a bucket, means on said bucket for suspending engagement with said hook, slots in the lower edge of said board and correspondingly slotted supporting strips adapted for interlocking therewith and retaining the board in upright position.

2. A game comprising a flat board, a weighted projectile, and a catapult, independently adjustable with respect to said board and adapted to throw the weighted projectile toward and into said bucket.

6. A hook thereon, a bucket, means on said board, correspondingly slotted supporting strips adapted for interlocking therewith and retaining the board in upright position, Signed by me at Salem, Mass., this sixteenth day of October 1924.

SIDNEY W. KNIGHT.
